C. G. Page,

Door Bolt.

N° 17,843.

Patented July 21, 1857.

UNITED STATES PATENT OFFICE.

CHAS. G. PAGE, OF WASHINGTON, DISTRICT OF COLUMBIA.

CYLINDRICAL DOOR-BOLT.

Specification of Letters Patent No. 17,843, dated July 21, 1857.

To all whom it may concern:

Be it known that I, CHARLES G. PAGE, of Washington, in the District of Columbia, have invented an Improvement in Cylindrical Door-Bolts, and that the following is a full, clear, and exact description of the principle or character which distinguishes it from all other things before known and of the usual manner of making, modifying, and 10 using the same, reference being had to the annexed drawings, of which—

Figure 1 represents a common form of cylindrical bolt, and Figs. 2, 3, 4 and 5 represent my improvement. Fig. 6 represents 15 a displacement of the bolt.

My invention consists in an improvement in cylindrical door bolts described, represented and specified as follows.

Fig. 1 represents a common form of 20 cylindrical doorbolt, in which the bolt *a* is pushed back and forth by means of the handle or knob *b*, passing through the longitudinal slot or opening *c* in the guard plate *c'*. The cross slots *d d* are catches to receive 25 and hold the knob as the bolt is pushed back and forth so as to prevent the slipping of the bolt either way by pressure upon the end of the bolt or by the motion or jarring of the door. These bolts with their guards can be 30 made with great facility, the whole, with the exception of the brass knob *b* being cast of malleable iron. One of the most commonly experienced difficulties with these door bolts is that of pushing the bolt when it gets rusty 35 or when from changes in position the end of the bolt does not easily enter the catch plate or guard *e* Fig. 6. This latter difficulty is very common to door and shutter bolts in 40 consequence of the settling or swagging of the doors and shutters or their shifting positions from various causes. It becomes very often necessary to lift up a door by taking hold of the knob of the latch before the bolt can be entered and then the not unfrequent 45 result is the sudden slipping of the bolt into place, attended with risk of injury to the hand and also to the bolt itself from the concussion, and the door-knob is also liable to be deranged or broken by using it to lift the 50 door. It sometimes requires so much power to slip the bolts that a child or feeble person could not work them at all, and furthermore in the dark another difficulty arises from the necessity of getting the neck of the knob or 55 handle *b* directly in the longitudinal slot *c* before the bolt can be pushed endwise, and

lastly the power exerted to drive the bolts is considerably wasted for pressing upon the handle to move the bolt forward or backward causes the bolt to bind upon the 60 guards. All these difficulties are obviated by my improvement which consists in making the slot in the guard plate of the form and character shown in Figs. 2, 3, 4, 5. This slot *s* is oblique to the axis of the bolt except 65 at the end portion *m m* where it may be at right angles to the axis. The bolt is moved longitudinally by raising and depressing the handle *b* which presses alternately (in the back and forth motions of the bolt) against 70 the inclined sides of the slot, and thus exerts a powerful leverage in overcoming resistances to the motion of the bolt. It is a fact familiar to almost everyone using the common bolts that a rusty bolt or one that moves 75 hard from any cause is pushed with greater ease by giving it a rocking or partially rotating movement, at the same time that it is moved endwise, and it will be seen at once that my improvement takes full advantage 80 of this rotary movement in overcoming friction. To further facilitate the action of this bolt in cases of displacement I taper its 85 ends or make them conical as seen in Fig. 6, by which the entering of the bolt is secured for all ordinary displacements of the parts and it is found that with these provisions but little strength is necessary to lift a swagged door or shutter by the power of the bolt alone. The movement is simple and efficient, may be made in the dark as well as in 90 the light, and to check the bolt or prevent its slipping longitudinally when fastened or unfastened the end portions of the slot *m m* are not inclined, so that when the neck of the 95 handle *b* is within these portions the bolt cannot be moved either way by endwise pressure, which could be done when the neck of the handle is in the inclined part of the slot.

This bolt will answer for a right and left bolt either by elongating the bolt, and cutting off the rounded end *x* of the guard-plate or by making two slots as shown in Fig. 3. The slot may also be carried across the guard as shown in Fig 4. Either of the forms will answer for upright bolts and one side of the straight portion of the slots may in that case be notched out a little so as to receive the stem of the handle to more effectually prevent its jarring out of place, but the single cross slot it must be observed is not so well 100
105
110

suit to a horizontal bolt for doors, it being unsafe to leave the handle up, either when the bolt is fastened or unfastened, for the weight of the handle in case the bolt works loosely will cause it to run down the oblique slot and move the bolt through its whole range, one way or the other, but in the case of the zigzag or return slot shown in Fig. 2, the handle is always in a dependent position, as it is in the common right and left bolt shown in Fig. 1. These "power bolts" as they may be called can be made or cast as readily and cheaply as the common bolts; the handle of the bolt being used as the lever for moving the bolt and no extra or additional parts being introduced while at the same time the guard plates can be made much stronger than in the common bolts, especially by using the single cross slot of Fig. 4. If it should be desired a cylindrical collar or antifriction roller may be slipped on the stem or handle *b* before it is secured in the bolt. This would facilitate the operation of the bolt when it binds hard from rust or other causes and would add but a trifle to the expense of each bolt. 25

What I claim as my improvement in cylindrical door bolts is—

1. The oblique slot in the guard in combination with the lever or handle of the bolt 30 working in said slot as set forth.

2. I also claim the zigzag or return slot *s* in the guard as shown in Fig. 2 by which the bolt is carried through its range by the two movements of raising and depressing the 35 handle as set forth.
